CLAIM

The ornamental design for disconnect fuse holder assembly, as shown and described.

DESCRIPTION

FIG. 1 is a front perspective view of a disconnect fuse holder assembly, showing our new design;
FIG. 2 is a right-hand side elevation view thereof with the left-hand side being the mirror image thereof;

FIG. 3 is a top plan view thereof with the bottom being the mirror image thereof;

FIG. 4 is a front elevational view thereof;

FIG. 5 is a rear elevation view thereof; and,

FIG. 6 is a front elevational view of another assembly without the indicia of FIG. 4 and the right, top and rear views are identical to FIGS. 2, 3 and 5 respectively.

UNITED STATES PATENT AND TRADEMARK OFFICE
CERTIFICATE OF CORRECTION

PATENT NO. : DES. 336,073

DATED : June 1, 1993

INVENTOR(S) : David R. Marach, et al

It is certified that error appears in the above-identified patent and that said Letters Patent is hereby corrected as shown below:

On the title page, item [19], delete "Happ" and insert therefor
--Marach--.

On the title page, item [75], delete named inventor, and insert
therefor the following:

David R. Marach, Marengo, IL

Conrad Alfaro, Chicago, IL

Lawrence R. Happ, Mundelein, IL

Signed and Sealed this
Twelfth Day of October, 1993

Attest:

BRUCE LEHMAN

Attesting Officer

Commissioner of Patents and Trademarks
